UNITED STATES PATENT OFFICE.

WILLARD M. MINER, OF THURLOW, PENNSYLVANIA.

TELEGRAPHIC REPEATER.

SPECIFICATION forming part of Letters Patent No. 331,250, dated November 24, 1855.

Application filed July 8, 1855. Serial No. 170,930. (No model.)

To all whom it may concern:

Be it known that I, WILLARD M. MINER, of Thurlow, in the county of Delaware and State of Pennsylvania, have invented a new 5 and useful Improvement in Telegraphic Repeaters, of which the following is a specification.

My invention has reference to telegraphic repeaters; and it consists in certain improvements fully set forth in the following specification, and shown in the accompanying drawings, which form part thereof. Telegraphic repeaters as heretofore constructed were complicated, involving a large number of adjustments before being operative, the delicacy of which adjustments was such that very few operators were capable of keeping the instrument in working condition.

The object of my invention is to so simplify a repeater that it shall be extremely simple, involving the use of but two instruments devoid of complications, the adjustments thereof being similar to those of a simple relay or sounder. By this it is seen that the repeater 25 is very inexpensive to make, and any ordinary operator might with but very little practice quickly adjust it to suit lines of various resistances.

In the drawing is shown an elevation of the 30 two repeating-instruments proper, and a diagram representing the circuits, connections, batteries, keys, &c.

A and B represent two main lines united by the repeating-instruments and connections.

C are the main batteries.

D and D' represent two keys for making and breaking the main-line circuits, and are connected, respectively, by wires K and K', with contact-screws J on the repeating instruments proper, E E', and contact-pins p of switches Q.

E and E' represent the repeating-instruments proper, which are both made alike, consisting of the electro-magnet F, which attracts 45 an armature-lever, G, whose movement is limited by screws W, and is furnished with a back contact, H, which, when the armature is drawn away from the electro-magnet by the spring M, closes the circuit through the spring 50 I, drawing it away from contact with the contact-screw J, which spring I is connected by

wire L with contact P of the switch Q. The switch-lever Q, connecting with line A and instrument E, is connected by wire R with the electro-magnet F of the instrument E', and 55 the other pole of the said electro-magnet is connected by a wire, O, with the ground. The electro-magnet F of the instrument E is coupled up in a similar manner with the switch Q, connecting with the line B and instrument 60 E' and the levers G of the said instruments E and E' are connected by wires N with the ground, wires O of the opposite instruments from that on which they are located, and said circuits are furnished with local batteries 65 N'.

From an inspection of the diagram it will be seen that the instruments and circuits on each of the lines A and B are identically the same, and are coupled up in sympathetic working condition by wires N and R.

A close examination of the instruments E and E' will show that they are substantially similar to any sounder or relay, with an additional back contact to switch a current over 75 two different paths, or two currents over the same path, without breaking it or them both at the same time.

If desired, the instruments E and E' may be used as sounders, in which case the armature 80 G, striking between the stop-screws W, gives the sound, or they may be used as relays, in which case a local circuit, S, having a local battery, T, and a sounder, U, in circuit therewith, may be made or broken by the armature 85 G playing between the contact-screw W. In this latter case the upper or lower screw should be insulated, so that the armature G only completes the local circuit when drawn down.

When the switches Q are turned so as to be 90 upon the contacts p, as indicated in dotted lines, then the instruments E and E' are directly in circuit, respectively, with the lines B and A, and may be operated like any ordinary sounder or relay, each acting as a terminal instrument to its line without repeating; but when the switches are turned to contacts p, as shown in solid lines, then the current from either line is caused to pass through the repeating-points of one of the instruments E 95 and E' and through the electro-magnet F of the other of said instruments.

If the key D in line A is closed and a message is being sent by key D' in line B, and if we consider said key D' open the current from line A will be broken by the back contact H of instrument E pressing the spring I away from contact J; hence no current from line A passes through magnet F of instrument E', and when key D' is open, as shown, the current from line B is broken; but one of the local batteries N' acts through its circuit N, contacts H I of instrument E, wire L, switch Q, and wire R, through electro-magnet F of instrument E' which thus energized holds down its armature, keeping closed the circuit through contact J and I of line B. Now, should the key D' be depressed, the current from line B will pass through wire K, contacts I J of instrument E', wire L, switch Q, wire R, through electro-magnet F of instrument E, and by O to ground. This will energize the electro-magnet F of instrument E and the armature G will be depressed, raising the contact H and bringing contacts I and J together, which action closes line A through wire K, contacts J I of instrument E, wire L, switch Q, wire R, electro-magnet F of instrument E', by O to ground. From this it is seen that by either opening or closing the key D' the electro-magnet F of instrument E' always remains energized, so as to keep the contacts J and I closed, the said magnet being energized either by the current in the line A or the battery N' in the circuit N, and so long as the magnet of the instrument E' remains energized and the armature in the position shown, the impulses given by the action of the key D' will be repeated in the line A by the vibration of the armature G of instrument E, which alternately opens the line-circuit A and the circuit N, but never both at the same time; hence the proper impulses are sent down the line A without disturbing the position of the armature G of the instrument E', as electro-magnet F always remains energized so long as the key D is not operated. The same effect will take place if key D' be closed and the key D operated, only in this case the lever G of instrument E will remain attracted while the lever G of instrument E' will be vibrated.

The switches Q may be connected or coupled together, if so desired, so that both may be operated simultaneously, and the particular construction of the instruments E and E', is immaterial, as the details thereof may be modified in various ways without departing from my invention.

Having now described my invention, what I claim as new, and desire to secure by Letters Patent, is—

1. The combination, with the lines A and

B and their keys, of instruments E E', each consisting of electro-magnets F, armature G, contacts H I J, wires K, connecting the lines with the contacts J, wires L R, connecting the contacts I on one instrument with the electro-magnet on the other, and circuits N, having batteries N' and connecting contacts H of one instrument in circuit with the electro-magnet F of the other instrument, substantially as and for the purpose specified. 65 70

2. The combination, with the lines A B and their keys, of instruments E E', each consisting of electro-magnet F, armature G, contacts H I J, wires K, connecting the lines with the contacts J, wires L R, connecting the contacts I on one instrument with the electro-magnet on the other, circuits N, having batteries N', connecting contact H of one instrument in circuit with the electro-magnet F of the other instrument, wires K', connecting with each of said lines, and switches Q to connect the electro-magnets F in circuit with either wires K or L, substantially as and for the purpose specified. 75 80 85

3. The combination of the lines A B and their keys with instruments E E', each consisting of electro-magnets F, armature G, contacts H I J, wires K, connecting the lines with the contacts J, wires L R, connecting the contacts I on one instrument with the electro-magnet on the other, circuits N, having batteries N', connecting contacts H of one instrument in circuit with the electro-magnet F of the other instrument, and a local circuit having a sounder or other instrument located therein and controlled by the vibrations of the armature of the instrument E, substantially as and for the purpose specified. 90 95

4. In a telegraphic repeater, two electro-magnets, armatures therefor having each two circuit-closing contacts, one of which closes when the armatures are up, and the other when the armature is down, but in which both contacts in one instrument are never both opened at the same time, two line-circuits connecting, respectively, with one or the other of the contacts of said instruments, according as to whether the armature is up or down, lines connecting one of said contacts on each instrument with the electro-magnet of the other instrument, and local circuits having batteries connecting the other contact of each instrument with the electro-magnet of the other instrument, substantially as and for the purpose specified. 100 105 110 115

In testimony of which invention I hereunto set my hand.

WILLARD M. MINER.
